CLAIM

We claim the ornamental design for a media processing device, as shown and described.

DESCRIPTION

FIG. 1 is a front perspective view of an example media processing device;

FIG. 2 is a bottom rear perspective view thereof;

FIG. 3 is a top view thereof;

FIG. 4 is a bottom view thereof;

FIG. 5 is a front view thereof;

FIG. 6 is a rear view thereof;

FIG. 7 is a first side view thereof; and,

FIG. 8 is a second side view thereof.

Broken lines immediately adjacent the shaded areas depict the bounds of the claimed design while all other broken lines are directed to environment. The broken lines form no part of the claimed design. The wire frame lines shown throughout indicate surface contour.
